UNITED STATES PATENT OFFICE.

GEORGE B. RATTERMAN, OF NEW YORK, N. Y.

STAND FOR ELECTRICALLY-HEATED UTENSILS.

Application filed June 4, 1925. Serial No. 34,874.

This invention relates to a stand for electric irons and other electrically heated utensils, which is constructed with a special view to securing attractiveness of appearance, convenience of manipulation, and safety from fire.

More specific objects of the invention are to provide a support adapted to be rocked by gravity to turn the current on or shut it off from a utensil supported thereby, to conserve the electric current, and to prevent overheating of the utensil, to prevent unnecessary dissipation of the heat, and to provide means for automatically cutting off the current to avoid danger of fire, whenever the current is left on and forgotten.

The above and other objects and advantages of the invention will be more particularly explained in connection with the accompanying drawings, which illustrate one specific embodiment thereof.

In the drawings:

Figure 1 is a plan view of the invention.

Figure 2 is a vertical section taken on the line 2—2 of Figure 1.

Figure 3 is a horizontal section taken on the line 3—3 of Figure 2.

Figure 4 is a vertical section taken on the line 4—4 of Figure 1.

Figure 5 is a vertical section taken on the line 5—5 of Figure 2.

The stand, which is the subject matter of the invention, comprises a substantially rectangular frame having upwardly and inwardly sloping sides and ends 10, and having angular feet 11 secured at the lower corners thereof, and provided with suitable pads 12 so as not to injure the surface on which the stand rests. Secured inside of one of the end walls 10 is a combined switch and fuse box 13 formed of suitable insulating material, and having conductor bars 14 and 15 secured therein, and projecting through the adjacent end wall and through an insulating plate 16 secured to the outer side of the wall. The projecting ends of the bars 14 and 15 are adapted to be connected to the house current by a suitable connector 17. Secured in the other end of the box 13 are two other conductor bars 18 and 19, which are adapted to be connected by a connector 20 to an electric iron 21, or other electrically heated utensil. The iron 21 is adapted to be supported on a plate 22 preferably of as-

bestos, this plate being mounted in a rectangular frame 23, within which it is held by suitable cleats 24.

The frame 23 is pivotally supported from the frame 10, at one side of its center of gravity, as indicated at 25. The outer edge 60 of the frame 23 has downturned flanges 26, which overhang the sides and ends of the frame 10, and the upper side edges of the frame 10 have a slight downward slope at each side of the pivot 25, as best shown in Figure 4, so that the frame 23 has a limited rocking movement.

The conductor bars 15 and 18 have upstanding opposed spring clips 27 secured thereto, which are adapted to be connected by a contact member 28, which is secured to one end of the frame 23 and insulated therefrom. When the iron 21 is placed on the end of the plate 22 which is marked "Off", the contact between the member 28 and the clips 27 will be broken, and in order to prevent possible arcing, when the device is in this position, a tongue 29 of insulating material is secured in depending relation to the member 28 and separates the clips 27 when they are electrically disconnected. The conductor bars 14 and 19 are connected by a fuse 30. This fuse is located directly beneath the end of the plate 22 marked "On", so that in case the iron rests thereon for a long enough time to become overheated, the heat transmitted from the iron through the plate 22 will be sufficient to melt the fuse 30 and interrupt the current. The fuse 30 is separated by a flange or partition 31 from the conductor bars 15 and 18, and ribs 31^a separate the conductors 15 and 18 from the conductors 14 and 19, respectively. The box 13 is covered by a lid 32, which is provided with a slot 33 through which the contact member 28 projects, and is provided with an elongated opening 34, so that the fuse 30 may receive the full effect of the heat transmitted through the plate 22.

When the iron is removed from the stand, the latter is adapted to be rocked by gravity to close the circuit through the iron while it is in use. In case, however, it becomes too hot, the frame 23 may be held in "Off" position by means of a pivoted latch 35, which is adapted to be engaged underneath a stud 36 secured to the end of the frame 10 opposite to the box 13.

The surface on which the stand rests is further protected from the heat by a fender 37, which is supported underneath the box 13, and is provided with an asbestos lining 38. The corners of the fender 37 are provided with legs 39, which are adapted to rest on the feet 11. The corners at one end of the fender are cut out, as shown at 40, and the legs 39, adjacent thereto, are pivotally mounted so that they may be swung to one side of the feet 11 to permit the fender 37 to be assembled in position or removed.

It will be noted that when the iron is being used, the circuit is normally held closed by gravity. When the use of the iron is temporarily discontinued, it may be placed on the plate 22 at the "Off" side of the pivot 25, and its weight will automatically rock the plate and break the circuit. If the iron becomes too cool, it may be placed on the "On" side until it again becomes heated.

When the ironing has been finished, it is advisable to lock the circuit open by means of the latch 35. In case, however, the iron should be left too long on the "On" side through carelessness or forgetfulness, the heat of the iron will gradually penetrate through the plate 22 until the chamber, formed between said plate and the fender 37, becomes hot enough to melt the fuse 30. The opening 34 permits direct access of the heat into the fuse receptacle. The box 13, containing the fuse 30, conductor bars 14, 15, 18 and 19 and the spring clips 27, is a self-contained unit, which may be easily installed. All of the operative parts of the device are contained within the frame 10 beneath the plate 22, so that the device presents an attractive appearance, and the parts are protected against injury.

While the stand is primarily adapted for use in connection with an electric iron, it is obvious that it may also be conveniently used to support electric percolators, toasters, electric heaters and other appliances. It is preferred to turn the stand upside down when it is used for supporting as electric heater, and for supplying current to the heater, electric contacts may be made through the asbestos 38 into a switch which will be so arranged that current can be supplied therethrough only when it is in that position.

It is also obvious that various other modifications may be made in the construction and arrangement of the different elements of the invention without any material departure from the essential features thereof. It is my purpose, therefore, to include all such modifications within the scope of the appended claims.

What is claimed is:

1. In a stand for electric irons and the like, the combination of a frame, a box composed of insulating material and secured at one side of the frame, two pairs of conduc-

tor bars secured within said box and adapted to be connected respectively to the house wiring and to an electric iron, a fuse normally connecting one bar of each pair to each other, opposed spring members connected respectively to the other two bars, a plate pivoted at one side of its center of gravity to the upper part of the frame and adapted to support the iron, a contact member depending from the larger end of said plate in position to bridge the space between said spring members when the plate is left free to swing by its own weight, the weight of the iron when placed on the smaller end of the plate being sufficient to swing the plate in the opposite direction and break the contact, the melting point of the fuse being such that it will be melted by the heat from the iron whenever the latter rests on the plate above it long enough to become overheated.

2. In a stand for electric irons and the like, the combination of a frame, a box composed of insulating material and mounted at one side of the frame, two pairs of conductor bars secured within the box and adapted to be connected respectively to the house wiring and to an electric iron, a fuse normally connecting one bar of each pair to each other, opposed clips connected respectively to the other two bars, a plate pivoted to the frame with one end over the box, an insulated contact member depending from the plate and movable therewith into or out of contact with said clips to make or break the circuit as the plate is swung about its pivot, said plate being so balanced that with the weight of the iron on one end thereof the circuit will be closed, and with the weight of the iron on the other end the circuit will be open, the melting point of the fuse being such that it will be melted by the heat from the iron whenever the latter rests on the plate above it long enough to become overheated, thereby preventing waste of current and danger from fire.

3. In a stand for electric irons and the like, the combination of a frame, a box composed of insulating material and secured within one side of the frame, two pairs of conductor bars secured within the box and adapted to be connected respectively to the house wiring and to an electric iron, a fuse normally connecting one bar of each pair to each other, opposed spring members connected respectively to the other two bars, a plate pivoted to the upper part of the frame and adapted to support the iron, and a contact member depending from the plate in position to bridge the space between said spring members when the plate is rocked in one direction and to break the connection when the plate is rocked in the other direction, a lid secured to said box and hav-

- ing an opening above the spring members through which said contact member projects, and an opening above the fuse to promote the transference of heat thereto from the iron when the latter is resting on the plate above the same.
4. In a stand for electric irons and the like, the combination of a frame, a box composed of insulating material and mounted within the frame, two pairs of conductor bars secured within the box and adapted to be connected respectively to the house wiring and to an electric iron, a fuse normally connecting one bar of each pair to each other opposed spring members connected respectively to the other two bars, an asbestos plate pivotally supported at one side of its center of gravity by the upper part of the frame and adapted to support the iron, a contact member depending from the larger end of said plate in position to bridge the space between said spring members when the plate is left free to swing by its own weight, the weight of the iron when placed on the smaller end of the plate being sufficient to swing the plate in the opposite direction and break the contact, a lid secured to said box and having an opening above the spring members through which said contact member projects, and an opening above the fuse to promote the transference of heat thereto from the iron when the latter is resting on the plate above the same, the melting point of the fuse being such that it will be melted by the heat from the iron whenever the latter rests on the larger end of the plate long enough to become overheated.
5. In a stand for electric irons and the like, the combination of a frame, a box composed of insulating material and mounted within the frame, two pairs of conductor bars secured within the box and adapted to be connected respectively to the house wiring and to an electric iron, a fuse normally connecting one bar of one pair of a corresponding bar of the other pair, opposed spring clips connected respectively to the other two bars, a plate pivoted to the frame with one end over the box, an insulated contact member depending from the plate and movable therewith into and out of contact with said clips to make or break the circuit as the plate is swung about its pivot, said plate being so balanced that with the weight of the iron on one end the circuit will be closed, and with the weight of the iron on the other end the circuit will be open, a fender extending across the frame underneath the box and forming with the plate and frame a closed space to retain the heat conducted from the iron as the latter rests on the plate above the contact member, the melting point of the fuse being such as to insure its fusion whenever the iron rests on the plate above it long enough to become overheated, thereby preventing waste of current and danger from fire.
6. In a stand for electric irons and the like, the combination of a frame, a box supported within the frame, two pairs of suitably insulated conductor bars secured within the box and adapted to be connected respectively to the house wiring and to an electric iron, a fuse normally connecting one bar of one pair to the corresponding bar of the other pair, spring clips connected respectively to the other two bars, a plate pivotally mounted in the frame above the box and adapted to support an electric iron, a contact member depending from the plate in position to bridge the space between said spring clips when the plate is rocked in one direction and to break the connection when the plate is rocked in the other direction, a fender extending across the frame underneath the box and forming with the plate and frame a closed space to retain the heat conducted from the iron as the latter rests on the plate above the contact member, the melting point of the fuse being such as to insure its fusion in case the iron rests on the plate above it long enough to become overheated, thereby preventing waste of current and danger from fire.
7. In a stand for electric irons and the like, the combination of a frame, a box mounted within the frame, two pairs of insulated conductor bars secured within the box and adapted to be connected respectively to the house wiring and to an electric iron, a fuse normally connecting one bar of each pair to each other, opposed spring members connected respectively to the other two bars, a plate pivoted to the frame and extending over said box and adapted to support an electric iron, a contact member depending from the plate in position to bridge the space between said spring members when the plate is rocked in one direction and to break the connection when the plate is rocked in the other direction, said contact member having a tongue of insulating material depending therefrom and separating the spring members, when the circuit is broken, to prevent arcing, the melting point of the fuse being such that it will be melted by the heat from the iron whenever the latter rests on the plate above it long enough to become overheated.
8. In a stand for electric irons and the like, the combination of a frame, a box composed of insulating material mounted within the frame, two pairs of conductor bars secured within the box and adapted to be connected respectively to the house wiring and to the electric iron, a fuse normally connecting one bar of each pair to each other, opposed spring clips connected respectively to the other two bars, a plate pivoted to the

frame with one end extending over the box, an insulated contact member depending from the plate and movable therewith into or out of contact with said clips to make or break the circuit as the plate is swung about its pivot, said contact member having a tongue of insulating material depending therefrom and separating the clips, when the circuit is broken, to prevent arcing, said plate being so balanced that with the weight of the iron on one end the circuit will be closed, and with the weight of the iron on the other end the circuit will be open, a lid secured to said box and having an opening above the clips

through which said contact member projects, and an opening above the fuse to promote the transference of heat thereto from the iron when the latter is resting on the plate above the same, the melting point of the fuse being such as to insure its melting whenever the iron rests on the plate above it long enough to become overheated, thereby preventing waste of current and danger from fire.

In testimony, that I claim the foregoing as my own, I have hereto affixed my signature.

GEORGE B. RATTERMAN.
